CLAIM

We claim the ornamental design for an apparatus for making, storing and dispensing shaved or crushed ice, or similar article substantially as shown and described.

DESCRIPTION

FIG. 1 is a front perspective view of the apparatus for making, storing and dispensing of shaved or crushed ice; FIG. 2 is a front elevation view thereof; FIG. 3 is a top plan view thereof; FIG. 4 is a left side view thereof; FIG. 5 is a bottom plan view thereof; FIG. 6 is a right side view; and, FIG. 7 is a rear elevation view.

In all the drawings, structure shown in ghost lines illustrate exemplary functional or optional structure and do not form a part of the claimed invention.
